UNITED STATES PATENT OFFICE.

JAMES H. KIEFER, OF DAYTON, OHIO, ASSIGNOR TO THE DAYTON ENGINEERING LABORATORIES CO., A CORPORATION OF OHIO.

AUTOMATIC CIRCUIT-CONTROLLING DEVICE.

1,230,172.

Specification of Letters Patent. Patented June 19, 1917.

Application filed August 24, 1911. Serial No. 645,887.

To all whom it may concern:

Be it known that I, JAMES H. KIEFER, a citizen of the United States, residing at Dayton, county of Montgomery, and State of Ohio, have invented certain new and useful Improvements in Automatic Circuit-Controlling Devices, of which the following is a full, clear, and exact description.

This invention relates to improvements in circuit controlling devices, more particularly for automatically breaking an electric circuit under certain conditions, and automatically reestablishing the same.

The devices shown herein are illustrated and described more particularly with reference to electric ignition systems, and it is one of the objects of the present invention to provide an automatic circuit controlling device which will be an advantage in ignition systems, in the way of increasing the efficiency of said systems and preventing misoperation or injury thereto.

But, it is to be understood that these improvements are not limited to ignition devices, but are applicable to other forms of electrical systems, wherein such automatic controlling features are advantageous.

As one of the objects of the present invention, in so far as applied to an ignition system, the aim is to prevent an excessive amount of current from passing through the main circuit of the ignition system, by providing an automatic circuit breaker which operates to break the main circuit or cut down the flow of current therethrough, whenever the main current rises beyond a certain predetermined point. Or, in another aspect, the object is to operate the circuit breaker automatically, after a certain time interval of flow of the current.

And at the same time it is one of the purposes of the invention to provide for the reestablishment of the circuit through the circuit breaker automatically, according to the condition of the apparatus in the main circuit.

Further objects and advantages incidental to the present invention will be apparent from the following description, reference being had to the accompanying drawing, wherein a preferred form of embodiment of the invention is illustrated.

Figure 1 is a partly diagrammatic view of the electrical circuits and connections embodied in the present invention, the arma-

ture of the controlling mechanism being shown in attracted position and the main circuit of said system being broken.

Fig. 2 is a detail view, partly in section, of the controlling or regulating element, the armature in the present view being shown in normal position.

It may be stated that in the particular form shown herein, the desire is to provide against deterioration of batteries supplying an electric current for the ignition circuit, wherein it sometimes occurs that the timing mechanism may come to rest at such a point that it leaves the contacts permanently closed. This would result in a continuous flow of the battery current, and a running down of the battery, and other disadvantages might also follow.

But, with the application of the present improvements, the system is provided with a circuit breaker which automatically breaks the main ignition circuit, in case the timer contacts should happen to come to rest at such a position. And then the apparatus is further arranged so that the circuit breaker remains locked in circuit breaking position, and stays this way until the timing mechanism of the main circuit is again set in motion, so as to break the main circuit, whereupon the circuit breaker is automatically released or actuated, so as to reestablish through it the main circuit connection and thus leave the system ready for operation by a continued movement of the timing mechanism.

Thus, in the particular mode of use, the automatic circuit breaker operates only under those abnormal or unusual conditions, wherein the timer has stopped on contact; but then the circuit breaker is automatically closed again as soon as the timer resumes its normal operation of breaking and making the circuit at that point.

It will be obvious from the description which follows hereinafter, that the same protective feature resides in this automatic circuit breaker, in case the main circuit is closed or grounded by any other means than the timer, so as therefore to prevent undue running down of the batteries.

It is furthermore one of the features of the present improvements that in bringing about the operation of this circuit breaker, use is made of an iron wire. The characteristics of such an iron wire are that upon passage

of abnormal amount of current therethrough, or for a prolonged time, the iron wire increases in resistance; this being sometimes expressed as having a positive coefficient of resistance.

Now, it will be seen that if this iron wire is utilized as part of the apparatus to operate the circuit breaker, by its heating effect, it follows that an increase of resistance thereof will at the same time serve the additional purpose of cutting down the flow of main current, so as to lessen any deleterious effects of the breaking of that current.

In Fig. 1, there is disclosed an ignition system, wherein a controlling or regulating mechanism is so arranged that upon a flow of current, over and above a predetermined amount, said regulating mechanism will tend to automatically, first, effect the reduction in the flow of current through the main circuit and secondly, upon a continuation of this flow of current, will positively effect the opening or breaking of the circuit, whereby the flow of current will be completely cut off, this condition being maintained until the mechanism is again placed in normal operating position.

In Fig. 1, the numeral 20 designates a supply or source of electrical energy, such as a storage battery or accumulator of approved type. One pole of this accumulator or battery is connected with the primary winding 22 of the induction coil, by means of the wire 21, while the opposite end of said primary winding is connected to the stationary contact 24 of the timing mechanism 25, by means of the lead wire 23. This stationary contact member of the timer is intermittently engaged or placed in contact with the movable contact plate 27, which in turn is actuated by means of the cam 28, driven through any suitable mechanism actuated by the engine.

It will, of course, be understood that it is not intended to limit the present invention to a system embodying a timer mechanism of the type herewith shown and described, but rather that any approved timer may be employed. The timer herewith shown and described, is substantially the same as that which forms the subject matter of the co-pending application of Charles F. Kettering, filed Dec. 15, 1911. Serial No. 592,291.

The timer cam 28 is electrically connected by means of the wire 29, with the variable resistance coil or winding 30, which surrounds a novelly constructed contact plate 31, of the controlling mechanism.

One end of the variable resistance coil 30, is secured directly to the contact plate 31, which in turn is normally in contact with the plate 33, said plate 33 being electrically connected to the battery 20, by means of the lead wires 34 and 35.

From the above, it will be obvious that the

path of current under normal conditions, will be as follows:—From the battery, the current will flow through the wire 21, primary winding 22 of the induction coil, wire 23, through the contact members 24 and 27, 70 and timer cam 28, into wire 29, by which it is conveyed to the variable resistance coil 30, contact plate 31, coöperating contact plate 33, into wire 34 and back to the battery via wire 35, it being understood that the contact 75 plates 31 and 33 are normally closed as is shown in Fig. 2.

So long as conditions remain normal, the above described path of the current will be unchanged, but upon event of the accidental 80 continued closing of the main circuit, either because the contacts of the timing mechanism are left in closed position, when the engine is stopped or in inoperative position or from any other reason; the variable 85 resistance coil 30, which is constructed of iron wire, will immediately tend to heat up, because of the continuous passage of an excessive amount of current therethrough. It is a well known property of iron wire, that as 90 its temperature or heat increases, the resistance thereof increases in a like degree; and it will therefore be obvious that the supply of current passing through the main circuit 95 will be reduced as the resistance thereof increases.

The means of controlling the passage of current through the main circuit of the ignition system, by interposing an iron wire resistance therein, which as has heretofore 100 been explained, possesses the property of increasing its resistance as its temperature increases, forms one of the main features of the co-pending application of Charles F. Kettering, filed Aug. 11, 1911, Serial No. 105 643,547, which in turn is a divisional application of the co-pending application of Charles F. Kettering, filed April 17, 1911, Serial No. 621,512.

As an improvement upon the devices 110 shown in the applications just referred to, and with advantages which will be apparent to those skilled in the art, the present invention embodies means controlled by the variable iron wire resistance, which will automatically effect the positive breaking or opening of the main circuit when the iron wire has become heated to a predetermined degree.

This means comprises the contact plate 31, constructed of any metal which has a high 120 coefficient of expansion, such for instance, as German silver, and a reinforcing plate 32 of less length than plate 31, consisting of a piece of metal having a low coefficient of expansion, relative to the metal composing the 125 plate 31. This reinforcing plate 32 may be of either thin sheet steel or iron or any metal which, as has been stated above, has a low coefficient of expansion, relative to the metal of which the plate 31 is made. These 130

plates which are clearly shown in Fig. 2, are soldered together, throughout their entire length and are wrapped or wound with any suitable insulating material, as is shown at 18. The iron wire coil 30 is located outside of this insulation, one end of said iron wire resistance being connected to the contact plate 31 or to the plate having a relatively high coefficient of expansion, as at 19. The 10 contact plate 31 is extended beyond the plate 32 as is shown in Figs. 1 and 2; the extreme outer end thereof, resting directly in alignment with one end of the pivoted armature 36, said armature having an insulated button 15 37, which is adapted to rest against the plate 31 and to maintain the same in the position shown in Fig. 1, when the armature is attracted by the energization of the core 47. The stationary plate 33 and the compound 20 plate 31 are mounted in any suitable insulating block 40. In order to maintain the contact plates 31 and 33 in normally closed position, the spring 41 is so mounted that one 25 end thereof, impinges the plate 31, directly over the point where the pivoted armature engages the under side thereof.

The pivoted armature above referred to, is mounted on an L-shaped frame 45, which supports the electro-magnet 46. This electro-magnet comprises a central core 47, rigidly secured at one end, to the frame 45 and is provided with a pole piece 49 at the opposite end and so positioned, that when the said core is energized, the pivoted armature 35 will be attracted by and drawn toward the said pole piece.

The magnet core 47 is provided with a winding of wire of relatively high resistance, as at 50, the opposite ends of which are connected respectively with the wires 52 and 53, the wire 52 connecting with the wire 29, which as has heretofore been described, connects with the iron wire resistance 30 and the cam 28 of the timer mechanism, while 45 the wire 53 is joined with the wire 35 which leads directly to the battery.

The arrangement of the secondary circuits together with the secondary winding of the induction coil which is shown at 55, may 50 be of the usual design, and inasmuch as they do not enter into the novel features of the present invention, no further description thereof will be given.

The operation of the entire controlling 55 system will be as follows:—The ordinary circuit of the current under normal conditions, has heretofore been described, and it is thought will be obvious from an inspection of Fig. 1. However, when the timer 60 contacts are brought to rest in the position shown in Fig. 1, thus closing the main circuit, it will be seen that the continuous flow of current will initially occur through the main circuit of the ignition system. This 65 continuous flow of current will necessarily

pass through the resistance winding 30, which as has heretofore been stated, comprises an iron wire, or other variable resistance member, having substantially the same properties that the iron wire possesses, 70 that is, the property of increasing its resistance as its temperature increases. This winding, however, when in its normal condition, is of much lower resistance than the fine wire winding 50. 75

Now upon a continuation of this flow of current, the temperature of the iron wire will gradually increase and with the corresponding increase in its resistance, will tend to cut down the flow of current through 80 the main circuit, to practically a negligible quantity. The heat generated or given off from the iron wire, when in this condition, will be introduced into the contact plate 31 and in a slight degree into the reinforcing 85 plate 32, carried by the plate 31. As has been explained heretofore, the plate 31 is composed of metal having a relatively high coefficient of expansion, as compared with the coefficient of expansion of the metal 90 forming the reinforcing plate 32 and as the heat increases in said plates, the tendency of the plate 31 to expand, will be retarded in a certain degree by the difference in the coefficient of expansion of the reinforcing 95 plate 32 and the plate 31, which will result in the bowing or warping of the plate 31, away from the contact plate 33, thus completely breaking the main circuit by opening contacts 31 and 33. 100

If some supplemental means were not provided to maintain the circuit in this broken or open condition, the contacts would immediately close, as soon as the plates 31 and 32 became sufficiently cool to retract them 105 from their expanded position. In order to maintain the circuit in open condition, throughout the time interval that the timer contacts remain in continued closed position, the wire 29 which connects with the resistance coil 30, is also connected at the point 56 with the wire 52, which joins with one terminal of the fine wire coil, or high resistance winding 50, while the opposite end thereof connects through the medium of the 110 wire 53, with the direct battery connection 35. 115

Supposing that the timer contacts are in closed position, as shown in Fig. 1, the current will first pass through the wire 21, 120 primary winding 22, wire 23, contacts 24 and 27, and into the timer cam 28, from whence it passes through the wire 29. The normal course of said current being to pass into the variable resistance coil 30, across 125 the contact points into the plate 33, and thence back to the battery, via wire 34. However, when the plate 31 becomes sufficiently heated to expand so as to break the contact between the plates 31 and 33, the 130

course of the current through the iron wire coil will be immediately cut off and shunted into the high resistance winding 50, through the wire 52. As soon as the current enters said coil, it tends to energize the core of the electro-magnet, which in turn attracts the pivoted armature 36, in such a manner that one end of said pivoted armature will be brought into contact with the plate 31, so as to maintain the opening between the plates 31 and 33; this condition being maintained throughout the time that the main circuit is closed by the inadvertent continued closure of the timer contacts.

From the above, it will be seen that the iron wire, together with the compound plate 31, will be entirely cut out of the main circuit, of the current, as soon as the break between the contacts 31 and 33 occurs, thus permitting the iron wire to cool off and regain its normal condition so that instantly upon the resumption of the normal operation of the cam member 28, relative to the timer contacts, the main circuit will be again intermittently closed and opened in the usual manner. The fine wire winding which surrounds the core 47 of the magnet, is of such high resistance that the amount of current passing therethrough, is very small, being only sufficient to maintain the core of the magnet in a sufficiently energized condition to retain the magnet in the attracted position, shown in Fig. 1.

From the above description, it will be obvious that as soon as the timer cam 28 assumes its normal operation, the main circuit will be broken and this will stop the flow of current through the fine winding 50, because of the difference in resistance between the main circuit and the winding 50. Now, as soon as the flow of current through this winding is stopped, the core 47 of the electromagnet will become deenergized, which will, of course, release the armature 36 from its attracted position, and through the action of the spring 41, the contact plate 31 will be forced back to its normal position, into engagement with the contact plate 33.

In some instances it may be desirable that the initial cutting down or tapering off of the current through the medium of the iron wire resistance be omitted from the apparatus and means employed, whereby the thermo-static contact plate 31 will, upon acquiring a certain temperature tend to act as heretofore described, and automatically break the main circuit.

This may be accomplished by simply replacing the coil of iron wire by a coil of any suitable electrical conductor, the current capacity of which will be less than the amount of current which will pass through said circuit, when the main circuit is closed for any extended period of time. In the use of some metals, as for instance copper,

in the make up of this coil, there will be no appreciable cutting down of the current, previous to the opening of the circuit, through the action of the thermostatic plate 31, but the introduction of heat into said plate and the consequent expansion thereof, will occur in substantially the same manner, regardless of the type of metal employed in the coil, so long as the conductive qualities of the current capacity of the same are suitably regulated.

While I have described a preferred form of one embodiment of my invention, it will be apparent that various changes in the combination and location of, and also the material or metal which comprises the various elements of the invention, may be made without departing from the spirit and scope of the present invention, as set forth in the following claims.

What I claim is as follows:

1. In a circuit controlling device, the combination with a source of electrical energy, and a main circuit connected therewith; of an automatic circuit breaker located in said main circuit and including a resistance which increases its resistance with increases of its temperature, said resistance operating upon said automatic circuit breaker to break the circuit through said resistance, upon an abnormal flow of current therethrough; said circuit breaker having provisions whereby the circuit through the resistance will be held open until the current in the main circuit is broken, when said provisions operate to reestablish the circuit through the resistance.

2. In a circuit controlling device, the combination with a source of electrical energy, and a main circuit connected therewith; of an automatic circuit breaker located in said main circuit and including an iron wire resistance connected in the main circuit, said circuit breaker also including a thermal device operated by the heating of the iron wire resistance to break the circuit through said resistance, upon an abnormal flow of current therethrough; said circuit breaker having provisions whereby the circuit through the resistance will be held open until the current in the main circuit is broken, when said provisions operate to reestablish the circuit through the resistance.

3. In a circuit controlling device, the combination with a source of electrical energy; a main circuit connected therewith; a make and break device adapted to open and close the main circuit; of a member having a positive coefficient of resistance connected with said circuit; a thermostatic circuit breaker controlled by said member to break the circuit through said member, upon an abnormal flow of current therethrough; and means operable by current from the main circuit to maintain open the circuit through

the member having a positive coefficient of resistance until the main circuit is broken.

4. In a circuit controlling device, a make and break device located in said circuit and adapted to close and open said circuit; an automatic circuit breaker also located in said circuit and including provisions operable to break said circuit when an abnormal flow of current occurs therethrough, due to the retention of the make and break device in circuit closing position; and means operable by the circuit current to maintain said circuit breaker in open position, but to close said circuit breaker when said make and break device moves into its position to break the circuit.
- 10
- 15

5. In a circuit controlling device, a thermo-electrical means normally in series with an electrical circuit and adapted to break said circuit, upon an abnormal flow of current therethrough; and electrically controlled means operable upon the opening of this circuit by said thermal means, for maintaining said circuit in open condition
- 20
- 25

6. In a circuit controlling device, a thermo-electric device connected with a main electrical circuit, whereby said circuit will be broken, upon an abnormal flow of current through said thermo-electric device; a shunt circuit including instrumentalities for maintaining the main circuit in open condition, until said circuit is broken at another point; and means for returning the instrumentalities to their normal position and to concurrently close the opening in the main circuit, which is effected by the operation of the thermo-electric device, as soon as the normal operation of the system is established.
- 30
- 35
- 40

7. In a circuit controlling device, a circuit breaker, comprising a pair of normally closed contact elements, one of said contact elements having a high coefficient of expansion; a conductive element having a positive coefficient of resistance connected to an electrical circuit; of an electrically actuated mechanism, comprising an electrical conductor having a normal resistance greater than the normal resistance of the
- 45
- 50

conductive element, and connected to the said circuit so that it is normally shunted by the conductive element, but is adapted to be placed in series with the said circuit when the normally closed contact plates have been initially opened.

8. In a circuit controlling device, a thermo-electric circuit breaker comprising a conductive element having a positive coefficient of resistance and a contact strip electrically connected with said conductive element and having a high coefficient of expansion, whereby when an abnormal flow of current passes through said element, having a positive coefficient of resistance, the said element will increase its resistance to cut down the flow of current therethrough, whereby when the resistance thereof reaches a determined point, the temperature of said element will be such as to cause the expansion of the contact element having a high coefficient of expansion and thus break the contact between said contact elements.

9. In a circuit controlling device, a thermo electric circuit breaker comprising an iron wire element and contact elements including a contact strip electrically connected therewith, and a reinforcing element associated with said contact strip, said strip having a high coefficient of expansion, whereby when an abnormal flow of current passes through said iron wire element, said element will initially increase its resistance to cut down the flow of current therethrough, the increased resistance thereof proportionately increasing the temperature thereof and thus causing an expansion of the contact strip so as to break the contact between the contact elements; and electrically controlled means adapted to be brought into operation by the actuation of the circuit breaker, for maintaining the contact between said contact elements in open condition until the flow of current has again returned to normal.

In testimony whereof I affix my signature in the presence of two subscribing witnesses.

JAMES H. KIEFER.
